ANTIHUNTING MEANS FOR REMOTE-CONTROL SYSTEMS

Filed Feb. 27, 1943

UNITED STATES PATENT OFFICE

2,475,269

ANTIHUNTING MEANS FOR REMOTE-
CONTROL SYSTEMS

Michel N. Yardeny, New York, N. Y.

Application February 27, 1943, Serial No. 477,469

4 Claims. (Cl. 318—31)

1

My invention relates to remote control systems and has particular reference to systems employing electric motors with control devices for bringing two or more controlled members into exact required positions.

My invention has further reference to control systems and apparatus in which a reversible electric motor is employed for operating a useful load, said motor having reversing windings connected directly or through a suitable relay or relays with two control elements for producing relative movements between the control elements, one of the control elements comprising a pair of conducting members separated by a gap and the other a contactor in a sliding engagement with the conducting members, the motor being so connected in a circuit with the control elements that it is stopped when the contactor engages the gap.

One of the main objects of my invention is to provide an apparatus or system whereby a useful load can be moved a predetermined number of complete revolutions and then a desired fraction of one revolution for one cycle of movement of the control elements. An apparatus of this type may be described as a "multi-revolution device."

Another object of my invention is to provide means for placing the conducting members accurately in any desired position, each pair of conducting members being capable of being adjusted within almost 360° or almost a complete circle.

Another object of my invention is to reduce sparking at the contacts between the conducting members and the contacts when rotation of the motor is reversed or when the motor is stopped. I accomplish this by using special relays consuming a very small amount of electric power; also by using condensers and resistors in the current interrupting circuits.

Another object of my invention is to provide an apparatus of the foregoing general type with further improvements for its satisfactory operation. One of such important improvements consists in the provision for suppressing and entirely eliminating oscillations or hunting of the motor when the contactor engages the gap and the motor must be stopped. I have found by actual experience that such a result can be obtained when using a combination of certain electrical and mechanical features as disclosed more fully in the appended specification. Certain of these features can be used, however, not only

2

with the remote control systems but also with other systems employing reversing motors.

I also provide means to combine electric with manual controls, to be used selectively, the oscillation-suppressing features being automatically eliminated when the manual control is used.

My invention is more fully described in the accompanying specification and drawings in which—

- 10 Fig. 1 is a diagrammatic view of my remote control system in one of its modifications;
 Fig. 2 is a similar diagrammatic view of the system, showing electrical connections;
 Fig. 3 is a detail view of a driving gear and
 15 friction clutch, taken on the line 3—3 of Fig. 2;
 Fig. 4 is a diagrammatic view of a system with a shunt motor; and
 Fig. 5 is a detailed view of an arrangement of
 20 the control elements.
 My remote control system is represented in
 one of its modifications in Figs. 1, 2 and 3, Fig.
 25 2 showing the complete circuit diagram. It con-
 sists of a reversible electric motor 1 with re-
 versing windings 2, 3, Fig. 2. The windings are
 connected at the common tap 4 by a lead and an
 30 interruptor 50, 51, 52 or leads 93, 94 and a rotary
 switch 53, 55, 56, 57 as will be explained more
 35 fully hereinafter; 5 with one terminal of a source
 of current 6, the other terminal being connected
 40 by a lead 7 with a contactor 8. The latter can
 be placed in any desired position by a manually
 or otherwise controlled device 9, indicated dia-
 45 grammatically in Fig. 1. The contactor has a
 pointer 10 indicating its position on a scale 11.
 The contactor also has a contact point 12 adapted
 50 to bridge the gap 13 between members 14, 15,
 made of a conducting material and which may
 be in the form of segments so that they will be
 55 for convenience called segments. The segments
 are connected by flexible leads 16, 17 with the
 ends of the coils 18, 19 of a suitable relay act-
 ing on switches 20, 21 for causing the switches
 to engage contact points 22, 23, connected
 through a lead 24 with the second terminal of
 the source of current 6. Normally the switches
 20, 21 engage contact points 22', 23' of the coils
 2, 3. It will be seen that current will flow
 through one of the relay coils 18 or 19 when the
 contact member engages by its pointed 12 one
 of the segments 14 or 15. The corresponding
 switch 20 or 21 will be then attracted by the en-
 ergized relay coil, causing the current also to
 flow through one of the motor field windings
 2 or 3. The motor will rotate in a correspond-
 ing direction, turning the segments through

worm 25 and 27 and worm gears 26, 24' or through some other gear arrangement. The pinion 25 may be connected by a shaft 29 with a useful load 30 which may be a tuning condenser, etc. The rotation will continue until the gap 13 is bridged by the contact member 12 whereby both relay coils will be energized with a result that both switches 20, 21 will be deflected, disconnecting the motor windings 2, 3. The motor will be therefore deenergized and stopped. The gap portion 13' is narrower than main gap 13 so as slightly to enlarge the extent of the contact surfaces 14, 15 and thus somewhat to increase the range of the possible positions of the disk, thereby also increasing the range of the possible load positions.

The segments are suitably mounted on a common shaft 29' with the gear 24', concentric with the shaft 28' of the contactor 8.

With the double gear reduction as shown, the shaft 29 of the load 30 will make several revolutions for one revolution of the indicator 10. It will be therefore possible to turn the shaft 29 through several revolutions and to stop the same exactly in a desired position as indicated by the pointer 10 on the scale 11.

Since it is preferable to use a small high speed motor with my system, it is also necessary to take steps to prevent overrunning of the indicated position by the rotating members by inertia, which overrunning may result in oscillations or hunting of the motor. One of such devices for suppressing motor oscillations is shown in Figs. 1 and 2 and consists of a flywheel 31, freely rotating on the motor shaft 28 but connected with the shaft by a friction clutch 32, pressed against the side of the flywheel by a spring 33. Pressure of the spring may be regulated by a nut 34. The effect of the flywheel is such that it will cause an increased drag on the shaft when the motor rotation is reversed, tending to retard the rotation after reversals and thereby stopping the hunting or oscillations.

An additional hunting-suppressing means consists of a frictional clutch between the gear 26 and shaft 29 as shown in Fig. 3. The gear is loosely mounted on the shaft 29 but prevented from rotation by a pin 35 engaging a slot 36. The latter, however, is sufficiently wide to allow for a certain amount of free motion of the gear on the shaft. The gear is further engaged to the shaft by a friction clutch plate 37, slidably keyed to the shaft 29 and urged by a spring 38 against the face of the gear. Spring tension can be adjusted by a nut 39, Fig. 3.

Tension of the clutch is so adjusted in relation to the resilient friction of the contact member 12 in the gap that the clutch will slide when the motor is deenergized by the gap being bridged by the contact member 12 and the motor continues to rotate by inertia only. The contact member will therefore be locked in the gap without any back and forth oscillations. Clutch friction will dissipate the inertia rotational energy of the motor, effectively stopping the latter while it is still deenergized.

Gears 40, 41 are provided for manual operation of the device as shown in Fig. 1. The gear 41 is mounted on a shaft 42, sliding in bearings 43 and being urged upward by a spring 44. The shaft can be rotated by a thumb head or handle 45 after it is depressed for bringing the gear 41 into engagement with gear 40. At the same time a cam 46 mounted on the shaft 42 engages one end of a lever 47 whose other end is pivoted at

48, the middle portion of the lever engaging a cup-shaped member 85, Fig. 3, with teeth 86, engaging corresponding holes 87 in the gear 26. A spring 88 normally keeps the cup-shaped or toothed member 85 away from the gear. With this arrangement the lost motion between the gear and the shaft 29 is eliminated when the manual control is used, the toothed member 85 being slidably keyed on the hub of the clutch member 37.

As an added arrangement for eliminating lost motion between the gear 26 and worm 27, the gear may be made of two parallel discs 26', 26, sliding in relation to each other but connected 15 together by helical springs 49 fitted in slots 49'. The springs are given initial tension when the gear is brought into mesh with the worm, causing the two halves of the gear to press at the worm teeth from the opposite directions.

I have also found that motor hunting is also largely suppressed when two successive worm drives are employed as shown in Fig. 2, because of the increased friction of such drives.

As an additional means to suppress oscillations 25 I use a vibrating interrupter 50, Fig. 2, connected in series with the motor in the lead 5. Current passes through the interrupter coil, vibrating armature or arm 51, and contact point 52 to which the armature is urged by a spring 89. A 30 resistor 50' is connected parallel to point 52 to suppress sparking. The interrupter is normally short circuited by wires 93, 94, extending to contact points 53, 57. The motor shaft consists of two portions, 28 and 54, connected together by 35 a hook 55 on the shaft 28 engaging a lug 56 on the shaft 54. The points 53, 57 are in electric contact with each other as long as the shaft 28 drives the shaft 54 in one or the other direction, but as soon as direction of rotation changes, i. e., 40 when the contactor 12 passes over the gap to the next segment 14 or 15, the hook 55 leaves the lug 56 and makes one revolution before engaging the lug again from the other side. In the meantime the leads 93, 94 are disconnected 45 so that the vibrator becomes operative, effectively stopping the motor when the contactor reaches the gap.

The effect of the vibrator is such that the motor 50 is slowed down when the contactor engages the segments at the gap, thereby losing its tendency to oscillate, rapidly reversing its rotation.

A lamp 60 or other suitable signal device can be placed in the motor circuit to indicate operation of the device.

55 A frictional clutch 53 (see Fig. 1) may be also provided between the shaft 54 and the worm so adjusted that the motor can drive the load through the clutch, but when manual means is used for turning the worm 27, the clutch permits 60 rotation of the worm without turning the motor shafts 28 and 54. Voltage for the relays may be reduced by the use of a potentiometer 148 or similar device such as transformer, etc.

To increase the accuracy of the control and as 65 means to suppress motor oscillations or hunting of the motor, provisions may be provided to increase friction between the contactor and the conducting segments at the gap. Such arrangements are shown in Fig. 5 and consist in raising the edges 138 of the segments 14 and 15. Such arrangements are of particular advantage when thin segments are used to avoid deflection of the segments by the pressure of the contactor. The 70 edges are raised at the main gap 13 only, the

other gap 13' being narrow, this gap never being bridged by the point 12 of the contactor 8.

To increase the accuracy of the system and as an additional means to suppress motor oscillations, provision is made to increase friction between the conductor and the conducting segments at the gap. According to Fig. 5, the edges of segments 14 and 15 forming gap 13 therebetween are raised at 138. The tips of the segments are bent downwardly to rest upon disk 72, thereby avoiding deflection of the engaged segments by the contact pressure.

As shown in Fig. 4 coil 50 is connected by means of leads 93, 94 to contact brushes 53, 57 engaging contact rings 97, 98 on the hubs of lug 56 and of hook 55.

A direct current motor 148 can be used with my system as shown in Fig. 4, current passing through the armature of the motor through leads 141, 142. A spark suppressing resistor 147 is included in the armature circuit. When one of the shunt field windings 2 or 3 is energized, the resistor is short circuited by a magnet 144, connecting the switch arm 145 directly with a lead 146. The transmission between motor 148 and segments 14, 15 is shown only diagrammatically and is of the same type as illustrated in Fig. 2.

I claim as my invention:

1. A control apparatus comprising relatively movable control elements; reversible drive means adapted to operate a useful load; transmission means arranged to be operated by the drive means for producing relative movement between the control elements, said transmission means being arranged to cause the control elements to complete one cycle of movement for more than one cycle of movement of the drive means; means to control the drive means by the relative position of the control elements, and to render the drive means inoperative in response to the control elements occupying a predetermined relative position; and anti-hunting means comprising means for reducing the rate of movement of the drive means and means for rendering the reducing means operative for a fraction of one cycle of movement of the drive means in response to a reversal of the drive means.

2. A control apparatus comprising relatively movable control elements; a motor; reversible rotary drive means operated by the motor and arranged to operate a useful load; transmission means arranged to be operated by the drive means for producing relative movement between the control elements, said transmission means being arranged to cause the control elements to complete one cycle of movement for more than one cycle of movement of the drive means; means to control the direction of movement of the drive means by the relative position of the control elements and to render the motor inoperative in response to the control elements occupying a predetermined relative position; and anti-hunting means comprising means to reduce the rate of

rotation of the motor by periodically interrupting its energy input and means to render the anti-hunting means operative for a fraction of one revolution of the drive means in response to the reversal of the direction of rotation of the drive means.

3. A control apparatus comprising relatively movable control elements; reversible drive means adapted to operate a useful load; transmission means arranged to be operated by the drive means for producing relative movement between the control elements, said transmission means being arranged to cause the control elements to complete one cycle of movement for more than one cycle of movement of the drive means; means to control the drive means by the relative position of the control elements, and to render the drive means inoperative in response to the control element occupying a predetermined relative position; and anti-hunting means comprising means for reducing the rate of movement of the drive means and means for rendering the reducing means operative for a fraction of one cycle of movement of the drive means.

4. A control apparatus comprising relatively movable electric control elements; a reversible motor adapted to operate a useful load; transmission means arranged to be operated by the motor for producing relative movement between the control elements, circuit means to control the motor by the relative position of the control elements, and to render the motor inoperative for the purposes aforesaid in response to the control elements occupying a predetermined relative position, the said transmission having a driving portion and a driven portion, dogs secured to the said portions and arranged with the driving dog in abutting driving relation with the driven dog, electric means for reducing the speed of the said motor included in a circuit with the motor, and a by-pass circuit including the said dogs and speed reducing means, the said driving abutment between the dogs completing the said by-pass circuit to render the speed reducing means normally ineffective and breaking the said by-pass circuit during the time the driving dog is disengaged from the driven dog upon reversal of motor rotation.
